UNITED STATES PATENT OFFICE.

CHARLES E. DATH, OF CHICAGO, ILLINOIS, ASSIGNEE, BY MESNE ASSIGNMENTS, TO
W. H. MINER, INC., A CORPORATION OF DELAWARE.

HAND BRAKE.

Application filed November 23, 1923. Serial No. 676,468.

This invention relates to improvements in hand brakes for railway cars.

One object of the invention is to provide a simple and efficient hand brake, wherein a high powered pull on the brake chain is had and either a slow graduated or quick full release may be obtained.

Another object of the invention is to provide a hand brake of the type indicated, including a hand wheel wherein the hand wheel serves the dual function of operating means for tightening brakes and operating means for releasing mechanism.

A more specific object of the invention is to provide a hand brake of the worm and nut type, wherein the nut is composed of sections which are displaceable to effect instantaneous release of the brakes.

Other objects and advantages of the invention will more clearly appear from the description and claims hereinafter following.

In the drawing forming a part of this specification, Fig. 1 is a vertical, sectional view through the end portion of a car, showing my improvements applied thereto. Fig. 2 is an enlarged, vertical, sectional view, partly broken away, of the split nut, housing and adjacent parts of the brake mechanism, the worm being shown in side elevation. Figs. 3 and 4 are horizontal, sectional views, corresponding, respectively, to the lines 3—3 and 4—4 of Figure 2.

In the drawing, 10 denotes the corrugated sheet metal end wall panel of a box car, 11 the roof, 12 an end plate, 13 an end plate facia board, 14 a platform for the brakeman and 15 an upper bearing bracket.

The improved hand brake mechanism comprises, broadly, a combined hand wheel, sleeve and housing A; a split nut B; a pull rod C; a combined pull rod guide bracket and bearing member D; and a combined pull rod guide and stop bracket E.

The combined hand wheel sleeve and housing A, comprises a hand wheel 16, a hollow cylindrical sleeve 17 formed integral with the hand wheel and downwardly extending from the hub thereof and a housing 18 formed integral with the sleeve. Although the hand wheel is shown as formed integral with the sleeve 17 it will be evident that the hand wheel may be detachably connected to the sleeve 17 by forcing the upper end of the sleeve with a square extension

adapted to accommodate the standard brake wheel held in position by the usual nut. The sleeve 17 is rotatably and slidably mounted in the bearing bracket 15. The housing 18 is of hollow, truncated, four sided pyramidal form and comprises vertically extending side walls 19—19, upwardly converging end walls 20—20 and a top wall 21, which forms a continuation of the sleeve 17. The housing 18 has the bottom thereof closed by a pair of plates 22. The plates 22 are of like construction and each is provided with an upwardly extending peripheral flange 23, and semi-cylindrical upwardly and downwardly projecting inner flanges 24, adapted to form a bearing sleeve when the parts are assembled. The bottom plates 22 are held in fixed position by screws 25, or any other suitable means, passing through the end walls 20 of the housing 18, and the flanges 23 of the plates 22. The side walls 19 of the housing 18 are provided with interior, upwardly converging pairs of relatively short ribs 26—26, spaced from the end walls and parallel thereto. As clearly shown in Fig. 2, the ribs 26 extend upwardly from the peripheral flange 23 and terminate at the lower side of the nut B, when the latter is in the extreme position at the upper end of the housing.

The split nut B comprises a pair of similar blocks 27—27. Each of the blocks 27 is provided with a flat outer face 28 similarly inclined to and adapted to co-act with the end walls 20 of the housing 18. The inner faces 29 of the blocks 27 are provided with interrupted threads 30 adapted to co-act with threads 31 at the upper end of the pull rod C. The blocks 27 also have their opposite side faces provided with grooves 32 similarly inclined to the ribs 26 to effect separation of the block sections 27 of the nut B, when the housing is moved upwardly. Upward movement of the nut within the housing is limited by contact with the top wall 21 of the latter.

The bracket D, which is rigidly secured to the end plate 12 and panel 10 of the car by means of bolts 33, is provided with an upwardly extending cylindrical sleeve portion 34, adapted to co-act with the semi-cylindrical flanges 24 of the housing 18, forming a bearing therefor. At the upper end, the sleeve portion 34 is provided with a peripheral flange 35 adapted to co-act with the up-

per ends of the cylindrical flanges 24 to limit the upward movement of the housing, and also adapted to form an abutment for the lower flat faces 36 of the nut section 27. 5 The brackets D and the sleeve portion 34 thereof are provided with a vertical bore 37 adapted to receive the pull rod C.

The pull rod C is mounted for vertical sliding movement in the platform 14, the 10 guide member D and guide member E. The guide member E is rigidly secured to the end panel 10 of the car, and the pull rod C is provided with a peripheral flange 38 near the lower end portion thereof adapted to co-act 15 with the bracket E to limit the downward movement of the same. To prevent rotary movement of the pull rod C, a vertical slot 39 is provided at the upper end thereof, which co-acts with a vertically extending 20 integral rib 139 on the interior of the sleeve portion 34 of the bracket D. The lower end of the pull rod C is connected to the brake mechanism proper by means of the chain 40 passing over the grooved pulley 41, journaled 25 in the bracket 42 rigidly secured to the end panel 10 and the bottom of the car.

The operation of the device is as follows. Upon rotation of the hand wheel 16, in a clockwise direction, with the nut in the position shown in Figs. 1, 2 and 3, the pull rod will be fed upwardly, rotation thereof being prevented by the rib 139 engaging within the slot 39. The upward movement of the pull rod C effects a tightening of the brake 30 chain 40, thereby applying the brakes. Rotation of the hand wheel 16 in a counter-clockwise direction will effect the reverse movement of the pull rod C, thereby gradually releasing the brakes. To effect a quick 35 releasing of the brakes, the hand wheel 16 is pulled upwardly, moving the housing 18 therewith and entering the ribs 26 within the slots 32 of the nut sections 27. Due to the converging arrangement of the ribs 26 and the grooves 32, separation of the sections 40 of the nut B will be effected, thereby disengaging the threaded portions thereof from the threads of the pull rod, entirely disconnecting the nut from the pull rod C and 45 instantly releasing the brakes. It will be evident that the nut sections will re-engage with the threaded portion automatically due to the weight of the hand wheel and attached parts causing the same to drop down as soon as the upward pull thereon is released, thereby moving the housing downwardly relatively to the nut sections 27, which are held in fixed position by abutment with the flange 35 of the bracket D, whereupon the 50 nut sections will be moved inwardly by co-acting inclined faces of the nut sections and the end walls 20 of the housing 18, again bringing the parts into operative relation, so that when the hand wheel 16 is again rotated in a clock-wise direction the brakes 55

will be applied as hereinbefore described. It will be evident that automatic means is thus provided for re-engaging the nut sections with the threaded portion of the pull rod as soon as the operator releases his hold 70 on the hand wheel so that the mechanism is ready for the next brake setting operation.

From the preceeding description, considered in connection with the drawing, it will be seen that my improved mechanism 75 provides for heavy pulls on the brake chain and that, in releasing the brakes, the brakeman may either gradually ease off the brakes when spotting the cars or release the brakes entirely at once, thus overcoming an objection sometimes made to hand brakes employing a self-locking worm arrangement.

I have herein shown and described what I now consider the preferred manner of carrying out the invention, but the same is merely 85 illustrative and I contemplate all changes and modifications that come within the scope of the claims appended hereto.

I claim:

1. In a hand brake, the combination with 90 a brake mechanism proper; of operating means therefor; and a releasable connection between said mechanism and means comprising a worm and a rotatable split nut, the split portions of said nut being bodily separable and slidably connected to said operating means.

2. In a hand brake, the combination with a pull rod having one end thereof provided with threads; of a rotary operating member; 100 a sectional nut carried by and rotatable with said operating member and longitudinally slidable with reference to the latter, said nut being adapted to co-act with the threaded end of said rod; and means including guides 105 for displacing the sections of said nut, at will, to release the brakes.

3. In a hand brake, the combination with a pull rod having one end thereof provided with threads; of a rotary operating member; 110 a split nut carried by and rotatable with said operating member, said nut being adapted to co-act with the threaded end of said rod; and means, including guides fixed with reference to said operating member for controlling the engagement of said nut and pull rod.

4. In a hand brake, the combination with a vertically, movable pull rod having a threaded upper end; of means for preventing rotation of said rod; a sectional nut co-acting with the threaded portion of said rod; a hand wheel; an operating shaft rigid with said hand wheel, said shaft being mounted for rotation and reciprocation; means for connecting said nut to said shaft for rotation therewith; and co-acting means on said nut and connecting means to effect disengagement of the sections of said nut from the worm to thereby release the brakes. 120 125 130

5. In a hand brake, the combination with a vertically movable pull rod having a threaded upper end; of a sectional nut co-acting with said threaded portions of said rod; a hand wheel; an operating shaft rigid with said hand wheel, said shaft being mounted for rotation and reciprocation; means for connecting said nut to said shaft for rotation therewith, said means being effective, upon reciprocation of said shaft, to separate the sections of the nut and release the brakes.

6. In a hand brake, the combination with a vertically movable pull rod member; of a rotary and vertically movable operating member having a hand wheel rigid therewith, said members having threaded engagement with each other to effect movement of said pull rod upon said operating member being rotated; and means associated with said operating member for disconnecting said members at their point of threaded engagement upon vertical movement of said operating member in one direction, thereby affecting instantaneous release of the brakes.

7. In a hand brake, the combination with a hand wheel having a housing and connecting shaft formed integral therewith; of a split sectional nut slidably mounted within

the housing and rotatable in unison therewith; co-acting means on the housing and nut for effecting separation of said sections; a pull rod having a threaded upper end co-acting with said nut; a plurality of brackets for guiding said pull rod for vertical sliding movement, said brackets and pull rod having co-acting means thereon preventing rotation and limiting the sliding movement, of said pull rod; a bearing bracket for guiding said shaft for rotary and vertical movement; and means on said last named bracket for limiting the vertical movement of the housing and forming an abutment of said nut.

8. In a hand brake, the combination with a brake mechanism proper; of operating means therefor; and means including a separable nut arrangement actuated by the force of gravity for connecting said operating means and mechanism, said second named means being manually operable to disconnect the same from said operating means and mechanism.

In witness that I claim the foregoing I have hereunto subscribed my name this 20th day of November 1923.

CHARLES E. DATH.
